UNITED STATES PATENT OFFICE

ERNST PAUL LEHMANN, OF BRANDENBURG-ON-THE-HAUEL, GERMANY

TOY

Application filed December 5, 1929, Serial No. 411,840, and in Germany December 5, 1928.

The invention relates to toys and comprises a body attached to a counter-weight by means of a cord which passes over a pulley the counter-weight being normally heavy enough to elevate the body which however is temporarily loaded with an additional weight whereby it is caused to move down an inclined or vertical track. As the body is generally constructed in the form 10 of a figure, either human or animal, it will be referred to subsequently as the figure.

Preferably one or more additional weights are mounted on projections or are otherwise suitably supported toward the upper 15 end of the track which the figure traverse in its upward and downward motion. The figure is so constructed as to pick up these additional weights or riders on its upward travel and the riders are of such weight as 20 to load the figure to make it heavier than the counter-weight. Consequently the figure, together with the rider, slides down to the lower end of the track where provision is made for depositing the rider. The 25 counter-weight which is heavier than the unloaded figure, then draws the latter to the top of the track again. If a plurality of additional weights or riders are provided and are arranged so as to be picked up 30 singly and in sequence, the operation is automatically repeated until the last rider has been deposited and the figure again drawn to the top of its track by the counter-weight.

Two embodiments of the invention are illustrated by way of example in the accompanying drawing:

Fig. 1 shows a toy with a trestle-like frame provided with two inclined tracks,

Fig. 2 is a front view of the same,

40 Figs. 3 and 4 show details thereof,

Fig. 5 shows a second embodiment having a column-like frame.

In the construction shown in Fig. 1 the frame is constructed in the form of a trestle with two inclined tracks *a*, *b*. Bodies *c*, *d* are displaceable along the two tracks *a*, *b* respectively and one of these bodies, for example *c*, may have the form of a figure. The bodies are of different weights and are 45 connected together by a cord *e* which passes

over a pulley *f*. In the example illustrated the body *d* is heavier than the figure *c*. Projections *g* are provided on the track *b* to receive auxiliary weights *h'*, *h''* . . . which can take the form of riders. The 55 lighter body *c* is provided with lugs *i*, *k* and every time the figure rises to the top one of these lugs serves to tip a rider from the projection on which it is carried, Fig. 3. The figure *c* is also provided with a bottom 60 ledge *l* on to which the rider falls when tipped off the projection on which it is placed. The additional weight remains in this position during the downward motion until its upper edge passes through an aperture *m* cut in the track *b* near the bottom of the frame. At the commencement of the operation the heavier body *d* must be raised. The lighter body or figure *c* may be held in its bottom position by hand or suitable 65 means such as a hook *n* may be provided for the purpose. As soon as it is released the operation occurs automatically as follows:

The lighter body or figure *c* rises to the top and tips the first rider *h'* in such manner 75 that this falls on to the bottom ledge *l* of the body *c* and loads it, making it heavier than the other body or counter-weight *d*. The figure *c* then travels down to the bottom of the track. In the lower end position 80 the rider *h'* falls through the aperture *m* provided in the track *b* so that the body *c*, again in the unloaded state, is the lighter and is raised to the top by the action of the heavier counter-weight *d*. On its upward 85 travel, the figure *c* picks up the second rider *h''* and the operation is repeated until all the riders have been removed. In Fig. 2 the arrangement is shown with the first two riders *h'*, *h''* already removed. In Fig. 3 the 90 figure is in the process of tripping the rider *h''*.

In the embodiment shown in Fig. 5 the frame has the form of a vertically disposed column. In this construction the projections *g* preferably are bent so as to form hooks, in order to facilitate the positioning of the riders.

I claim:

1. A toy comprising a pair of tracks in-

clined toward each other; a body on each track adapted to slide thereon; a flexible member connecting said bodies; a plurality of projections on one of the tracks near the top thereof, each adapted to receive a weight; and means on the body sliding on the track having the projections which is adapted on upward movement of the body to tip the weight from its projection so that it will fall into the body and be carried down thereby.

2. A toy comprising a pair of tracks, one thereof having a plurality of spaced projections near the top thereof adapted to receive a weight on each projection and an aperture at the bottom thereof; a pair of bodies adapted to slide on the tracks, one of which is a carrier body for the weights which slides on the track having the projections and the other is a counterweight body which slides on the other track; a flexible member connecting said bodies; and means on the carrier body adapted to directly tip the weights from the projections to be carried down the track in the body and dropped through the aperture at the bottom.

In testimony whereof I affix my signature.

30 ERNST PAUL LEHMANN.
